UNITED STATES PATENT OFFICE.

WILLIAM B. NELSON, OF CHICAGO, ILLINOIS, ASSIGNOR TO INTERSTATE IRON AND STEEL COMPANY, OF CHICAGO, ILLINOIS, A CORPORATION OF ILLINOIS.

COOLING BED.

Application filed April 15, 1922. Serial No. 553,258.

To all whom it may concern:

Be it known that I, WILLIAM BERGER NELSON, a citizen of the United States, residing at Chicago, in the county of Cook, State 5 of Illinois, having invented certain new and useful Improvements in Cooling Beds, do hereby declare that the following is a full, clear, and exact description of the same.

My invention relates to cooling beds used 10 in handling hot metal bars as they are delivered from the reducing-rolls of a rolling-mill, and consists in the novel and useful constructions herein described and then pointed out in the appended claims.

15 In the accompanying drawings, which illustrate a practical embodiment of my invention and in which the same reference numerals indicate similar parts in the different views, Fig. 1 is a top plan view of a longitudinal portion of a cooling bed equipped 20 with my invention, parts being broken away; Fig. 2 is a detail vertical sectional view on the line 2—2 in Fig. 1 with the parts in position when packs of bars are in place; Fig. 3 is a similar view showing the 25 parts in position when the packs are being advanced on the rack-section, and Figs. 4, 5 and 6 are detail sectional views on the correspondingly numbered lines in Fig. 1.

30 The practice of annealing hot metal bars in packs, as for example where flat bars are intended for use in making vehicle springs or other parts requiring a standard of hardness, is based on the theory that the heat 35 from the center of the pack will prevent the outer bars from cooling too fast and so anneal all its bars uniformly, and this has been carried on for many years by manually accumulating the bars in packs on the floor 40 of the mill, and more recently by mechanically accumulating them in packs on the cooling bed itself; in both cases they remained in pack formation until the critical temperature for annealing to the required 45 degree of hardness was passed. The first or so-called "hand-cooling" practice was unreliable and unsatisfactory to a very general extent, and it was uniformly necessary to subsequently anneal at least the outer bars 50 of the packs and frequently many of the inner ones, which involved a large outlay of time and money, the cost being at times prohibitive; in fact some spring steel is of such analysis that after "hand-cooling" it

would not pass the required Brinell test 55 which is the standard specification of vehicle spring makers unless it was later annealed. The other practice of mechanically packing the bars in the cooling bed and annealing them on the bed in process between 60 the reducing-mill and shears was a distinct advance as it did away with the manual labor of packing them by hand, but the bars supporting surfaces of the beds were so large 65 that they drew the heat from the contacting portions of the bars faster than the latter could absorb heat from the pack; the bottom bars and edges of the other bars in the pack were cooled so fast by the colder metal of the bed drawing heat from their contacting 70 portions faster than they could absorb heat from the pack that the heat of the pack was not sufficient to evenly anneal them and the contacting portions of the bars of the packs did not anneal to the same degree of hardness 75 as the rest of the bar. The critical temperature for properly annealing spring bars in a cooling bed is usually reached by the time the bar is ejected from the third pocket in the rack-section of the bed, and in the 80 early apparatus the chilled portions of the bars were below this temperature at this point so that the bars when finished were not uniform and did not meet the Brinell test. This chilling effect of the bed itself 85 was obviated by providing the supporting surfaces of the bed with staggered ribs, as shown for example in the co-pending application of George M. Smith, filed October 22, 1921, Serial Number 509,682, or with insulating pads as shown for example in my co-pending application filed October 22, 1921, Serial Number 509,648.

90 But in all cooling beds as heretofore constructed, so far as I am aware, the bars while 95 packed on the rack-section were exposed to air drafts passing through the racks between their webs and between the webs of adjacent racks, as well as to the cooling effect of the air above the rack-section, so that 100 the outer bars which are exposed broadside were air-chilled too fast and cooled below the temperature of the others and the heat from the center bars of the pack was not sufficient to evenly anneal them, and also it 105 frequently occurred that other bars in the pack were cooled so fast by the colder metal of the outer bars drawing heat from them

faster than they could absorb it from the pack that these inner bars were not properly annealed.

The object of my present invention is to provide certain new and useful improvements whereby the packs in the critical pockets of the rack-section of the bed are protected against air-chilling, and which obviate the air-chilling of the bars as a factor in annealing them in the bed in the process between the rolling-mill and shears.

Referring to the accompanying drawings which show my invention the reference letter A designates a long trough or run-out table provided with a series of feed-rolls *a* which project through the openings into the trough and convey the metal bar as it is delivered from the reducing-rolls. In practice the trough is usually long enough to accommodate a 300 foot bar, and the cooling bed, of which only a section is shown, is correspondingly extended.

The skid-section B of the bed includes a series of rigid inclined skid-beams *B'* having staggered vertical ribs *b* upon which the bars *x* are delivered from the trough. Between the beams *B'* are journaled in the bed a series of rocking-shafts *C* parallel with the beams and having arms *C'*, *C²* and *C³* extending therefrom; the arms *C'* on the ends of the shafts are arranged to pass through open-end slots *a'* in the trough A so that upon oscillation of the shafts they will transfer the bar out of the trough to the bed, and the other arms are arranged in staggered relation on opposite sides of each shaft and extend radially to project alternately into vertical position to form escape-
ment stops or dogs above the skids as the shafts are oscillated, the corresponding dogs of the shafts being arranged in a straight row extending longitudinally of the bed so that the hot metal bars *x* will be preserved in straight lines. Suitable mechanism which is well-known and forms no part of my present invention, and so need not be here shown and described, actuates the rocking-shafts so that they are simultaneously rocked back and forth to allow the bars lying on the skids to move by gravity successively down them from one row of dogs to the next lower row until they pass one by one from the last row upon the packing-device *B²* at the lower end of the skid-section B by which they are delivered to the first pocket of the horizontal section of the cooling bed.

The rack-section of the cooling bed is composed of a series of parallel horizontal racks *D* arranged respectively in line with the skid-beams as shown in Fig. 1. Each rack unit is composed of a flat base *d* and spaced vertical webs *d'* provided with a series of troughs or pockets *D'* which are V-shaped in cross-section, the corresponding pockets of the racks being arranged in

straight lines. Suitable mechanism of well-known construction, designated generally at *D²*, will be employed to lift and move the bars from each pocket and deposit them in the next one and discharge them upon the assembly-table (not shown), and the packing device *B²* will be formed of jointed arms and the lower arms will be actuated from below as now well-understood to deliver the bars from the skid-section of the bed to the first row of pockets in the rack-section so that they will be disposed therein in a pack as shown at *x'*; mechanisms for both these purposes are now well-known and need not be here described in detail, the transfer device *D²* being located and operated between the spaced racks, and the packing device at the front end of each rack. The racks are provided with supports *d³* by which they are mounted on the frame of the bed.

The initial or leading row of pockets in the rack-section is provided with a substantially continuous front closure; in the form shown each rack is provided with a baffle-plate *d⁴* at its front end which extends across the opening between its opposite pair of webs and projects laterally at each side beyond the webs, as clearly shown in Fig. 1 where the parts are broken away; the baffle-plates preferably are disposed in the inclined plane of the leading edge of the front pocket, and their adjacent edges are spaced apart sufficiently to provide clearance for the transfer mechanism *D²*, while they are notched in their upper edges between the webs as shown at *d⁵* to provide clearance for the packing mechanism *B²*. In practice each rack is preferably provided with a supplemental baffle-plate *d⁶* disposed in the inclined plane of the rear edge of the front pocket and extending laterally at each side to the same extent as the front baffle-plate *d⁴* and forming therewith a V-shaped crotch or trough the adjacent troughs being aligned lengthwise and forming a substantially continuous open-top trough or pocket having closed bottom and sides. The second and third rows of pockets in the webs are provided with angular pads *d⁷*, and the pads and baffle-plates are provided with vertical transverse ribs *d⁸* arranged in staggered relation. The front baffle-plate *d⁴* of each rack closes the passage between its webs, and as the ends of the adjoining baffle-plates are practically contiguous they also effectually close the passages between the webs of adjacent racks against the passage of any considerable volume or draft of air. In practice it is preferable to use the rear baffle-plates *d⁶* as they close the rear of the initial row of pockets and prevent air chilling of the successive bars as the front pack is built up in it; the first bars deposited in the front pack obviously are exposed to the air under different conditions than the later ones as

they temporarily are not subject to the heating action of others or of the completed pack, and so it is desirable to use the rear baffle-plates to prevent them from cooling 5 too fast. If desired the base plates d may be extended laterally to the same extent as the baffle-plates along the successive rows of pockets which with the front row constitute the critical portion of the rack-section 10 thus forming a floor in the rear of the open-top trough that is continuous except for the narrow slots between the adjacent bases through which the transfer mechanism D^2 operates. It will be apparent from Fig. 1 15 that this latter mechanism, which in pack annealing operates only periodically upon the completion of a pack in the front pocket may practically fill the slots between the adjacent racks when in its normal position, 20 and in any event the slots or openings are not of sufficient size to allow enough air to pass to affect the annealing of the bars as the area or extent of the metal exposed to each of them is so small and restricted that 25 it absorbs enough heat from the unchilled portions of the pack to prevent it from cooling faster than the pack itself. The front end of each base is notched as at d^3 to provide clearance for the means (not shown) 30 that operates the packing device.

The critical portion of the rack-section, usually comprising the first three or four rows of pockets, is provided with a cover E , which is suspended above the racks by any 35 suitable means that permits it to normally rest on the tops of the pockets as in Fig. 2 and move upwardly as in Fig. 3 when the transfer device moves the pack out of one pocket into the next pocket and then return 40 to its normal position. In the form shown the cover is suspended by a series of resilient arms E' fastened at one end to the cover and at the other end to the trough A . The cover is provided at its front edge with an up- 45 wardly and outwardly flared lip e so that the bars will readily and easily pass under it. The cover preferably is formed by a sectional flexible metallic plate and is long enough to extend the full length of the rack- 50 section of the bed; it may be wide enough to extend over either all of the critical pockets as shown in Fig. 4 or only the second and third of these pockets as shown in Fig. 2; in the former case its front side will be mo- 55 mentarily lifted or tilted by the movable packing arms sufficiently to allow the successive bars to pass under it, its flared lip guiding the bars to position and permitting them to cam its front edge upwardly from 60 the arms to permit their passage, and in the latter case its front edge will stand back of the position of the top bar of the pack, and its curved lip will wipe over this bar without disturbing it as the pack is transferred 65 to the second pocket. In either case the

cover is lifted by the transfer mechanism when a pack is moved from one pocket to the next, as clearly shown in Fig. 3, and when this transfer is completed it returns to its normal position on top of the racks. 70

When the bars are accumulated in packs on the rack-section the front baffle-plates d^4 close the passages between the webs so that no drafts of air can flow through them and chill the bars, and with the rear baffle-plates 75 d^6 form a trough that is practically closed at its bottom and sides to protect the bars from cooling too fast. The cover confines the heat in the pack and prevents it from rising and radiating into the outside air, 80 and also prevents this cooler air from chilling the bars, and when the rack-bases are extended laterally to the same extent as the baffle plates the floor thus formed forms a practically closed chamber in conjunction 85 with the cover.

I claim:

1. In a device of the class described, a rack having a series of pockets extending along its length, and a plate closing the 90 front of the initial pocket.

2. In a device of the class described, a rack having a series of pockets extending along its length, plates closing the front and rear of the initial pocket and constructed 95 to form an open-top trough, and a cover for a plurality of the pockets.

3. In a device of the class described, a rack-section constructed with vertical spaced webs having a series of pockets, extending 100 along their length, plates closing the front of the initial pocket between the webs, a cover above a plurality of the pockets of the section, and resilient means constructed to suspend the cover in its normal position. 105

4. In a device of the class described, a rack-section composed of a series of racks constructed with vertical spaced webs having a series of pockets, plates on the racks closing the front and rear of the initial 110 pocket therein and extending laterally beyond the webs to close the passages between the webs of adjacent racks, a cover above a plurality of the pockets of the section, and spring-arms constructed to suspend the 115 cover in its normal position.

5. In a device of the class described, a rack-section composed of a series of racks constructed with flat bases and vertical spaced webs inside the margins of the bases 120 and having a series of pockets, plates on the racks closing the front of the initial pocket therein and extending laterally beyond the webs to close the passages between the webs of adjacent racks, a cover extending lengthwise of the section and covering a plurality of the pockets of each rack, and supports constructed to movably suspend the cover in its normal position. 125

6. In a device of the class described, a

rack-section composed of a series of racks
constructed with flat bases and vertical
spaced webs inside the margins of the bases
and having a series of pockets, plates on
the racks constructed to form an open-top
trough closing the front and rear of the in-
itial pocket therein and extending across the
passages between the webs of adjacent racks,
a cover extending lengthwise of the section
and covering a plurality of the pockets of
each rack, and spring-arms constructed to
movably suspend the plate in its normal
position.

7. In a device of the class described, a
rack-section composed of a series of racks 15
constructed with vertical spaced webs hav-
ing a series of pockets, plates on the racks
closing the passages between the webs, a
flexible plate covering a plurality of the
pockets of each rack and having its end 20
flared upwardly, and supports constructed
to movably suspend the latter plate in its
normal position.

In testimony whereof I affix my sig-
nature.

WILLIAM B. NELSON.
